(57) **CLAIM**

I claim the ornamental design for a fore end stock for a firearm, as shown and described.

DESCRIPTION

FIG. 1 is a right side elevational view of the fore end stock for a firearm, showing my new design;

FIG. 2 is a left side elevational view thereof;

FIG. 3 is a bottom plan view thereof;

FIG. 4 is a top plan view thereof;

FIG. 5 is a front elevational view thereof;

FIG. 6 is a rear elevational view thereof;

FIG. 7 is a rear perspective view thereof; and,

FIG. 8 is a rear perspective view showing a first alternative embodiment thereof.

The broken lines depict environmental structure that forms no part of the claimed design.
